ROLLER ROCK BIT

Buford M. Baker, Garland, Tex., assignor to Engineering Laboratories, Incorporated, Tulsa, Okla., a corporation of Oklahoma

Application July 20, 1949, Serial No. 105,838

2 Claims. (Cl. 255—313)

1

This invention relates to roller rock bits for use in the drilling of oil wells and the like and particularly to the arrangement of such bits with respect to the flow of flushing fluid therethrough.

It has long been common practice to drill oil wells and the like by rotating a string of drill pipe with a roller cone cutter rock bit attached to its lower end, and to circulate mud downward through the drill string, outward through the bit and upward around the outside of the drill string. Such roller cone cutter rock bits usually have three cones, but sometimes have only two and may have more than three. The purpose of this mud circulation is mainly to bring cuttings dislodged by the drill bit to the surface of the earth. It also has the effect of flushing cuttings from between the teeth of the roller cone cutters and, to a certain extent, lubricating the operation of the drill bit.

Originally, it was considered sufficient to simply discharge the mud from the shank of the drill bit at a point above the roller cutters. For this purpose a simple axial opening was provided through the drill bit shank. More recently, however, attempts have been made to control the flow of mud at the point of its discharge to accomplish a more effective cleaning of the spaces between the drill bit teeth. Thus for example, in United States Patent No. 2,104,823 to Sherman, the shank of the drill bit is shaped to divide the mud stream into separate jets, one for each cutter, and each jet is directed radially inward toward one of the cone cutters.

It has now been found that prior constructions are inefficient for two reasons. First, they do not keep the bottom of the hole free from cuttings, although they do effectively wash cuttings out of the well once the cuttings get up into the main mud stream. Secondly, these prior constructions do not effectively remove cuttings from between the teeth of the roller cone cutters.

In prior bits it has been found that cuttings will accumulate beneath the bit and that the teeth of the bit will wear against these cuttings without making appreciable progress in the cutting of the bottom of the hole. As a result, only very finely ground cuttings arrive at the top of the hole, although the mud stream would obviously carry much larger cuttings and the cutters of the bit would obviously cut much larger cuttings. Furthermore, when the bit is withdrawn from the hole the spaces between the teeth of the cutters are often packed with cuttings.

Accordingly, it is the purpose of the present

2

invention to assure a thorough flushing, at all times, of the very bottom of the hole, and at the same time, to assure a thorough cleaning of the spaces between the drill bit teeth by the jetting of the incoming mud tangentially along the faces of the roller cone cutters, from base to apex, where it will be most effective to remove cuttings from between the teeth.

The change in the bit necessary to effect the improvements of this invention is entirely to the shank or body portion of the bit. In a three cone bit, which is typical of the bits generally used today, although two and four cone bits are sometimes used, the shank or body portion of the bit terminates at its lower end in three downwardly depending legs, upon each of which is mounted a roller cone cutter, and there is a hole through the center of this shank through which mud is forced downwardly against the upper surfaces of the cutters. A part of this mud passes downwardly between the cutters to the bottom of the well but the major proportion passes outward into the well between the adjacent cutter cones and the lower edge of the shank between the downwardly depending legs thereof. In prior constructions there has been a considerable area left open for the escape of mud at the three points just under the edges of the shank and between the downwardly extending legs thereof.

Obviously, these three openings can not be completely closed, but it has been found that by making the lower edge of the shank, between the downwardly extending legs, fit closely to the teeth of the cones, without any more clearance than is necessary to assure free rotation, the escape of mud through these three openings can be greatly reduced and the major portion of the mud caused to circulate completely to the bottom of the well, thus rapidly removing cuttings from under the teeth of the cutters.

It has also been found that by so forming the shank, the mud passage terminates in definite and properly positioned jets, the spaces between the teeth can be cleaned much more efficiently and a much greater proportion of the mud stream directed against the bottom of the well.

Thus, in a three-cone bit, it has been found expedient to form a separate jet for each of the three cutter cones and to arrange each of these jets so that it projects mud along the face of the cone from the base towards the apex. It has also been found expedient to provide an additional jet, in the center of the shank, directed axially downward so that fluid from this jet will pass

directly downward over the points of the cones and onto the bottom of the well.

Further details and advantages of this invention will be apparent from the appended drawings and the following detailed description thereof.

In the drawings:

Figure 1 is a side elevation of a well drill;

Figure 2 is a bottom plan view of a well drill having one cutting cone mounted to the body portion thereof;

Figure 3 is a view in vertical section of a well drill bit constructed in accordance with the principles of the present invention, two of the cutter cones being removed for convenience of illustration; and

Figure 4 is a view in section taken along line 4-4 of Figure 3.

Now referring in greater detail to Figure 1, the shank 5 has an upwardly tapered and threaded portion 6 for engaging in a drill string and three downwardly extending legs 7. Upon these legs are mounted three cones 8 arranged so that their apexes converge toward the center line of the shank. The shank 5 is so constructed as to allow minimum space between the cutting teeth 9 and the shank. This is accomplished by extending the shank downward to form an enclosure between the three downwardly extending legs. This extended flange portion 14 of the shank forms a rounded concave central section at the lower end of the shank and will greatly minimize the escape of fluid over the top of the cutting teeth at this point. Fluid that does escape at this point obviously does no cleaning. With the arrangement as described, most of the fluid will be directed at the teeth and into the bottom of the hole being drilled.

In Figure 2 the cutting cones are formed with cutting teeth 9 arranged in circumferential rows around the tapering periphery of the cone. The rows of teeth on the cone mounted most outwardly from the apex of the cone are on a different taper than those in adjacent rows. Each adjacent row is offset longitudinally of the cone from each other adjacent row. The cutting cone 8 is mounted in the conventional way onto one of the downwardly extending legs 3.

Referring to Figure 3, the shank 5 of the bit has a centrally located mud channel 10. A circular baffle plate 11 with a centrally drilled hole 12 is mounted at the lower extremity of the mud channel within the body portion of the bit and having its periphery enclosed by the three downwardly extending legs 3. At its lower end the mud channel 10 is provided with three mud discharge conduits 13. These conduits are 120° apart around the mud channel and are positioned to correspond with each of the three downwardly projecting legs. These conduits form a passage for the mud or flushing fluid so as to direct the fluid around the baffle plate 11 and onto the cutting teeth 9. It will be noted that this arrangement causes the fluid to impinge upon the teeth from their base ends instead of directly against their faces.

In Figure 4 the baffle plate 11 is located at the lower end of the mud channel 10 and mounted with relation to the mud discharge conduits 13 so as to allow the flushing fluid from the mud channel 10 to pass around this baffle plate and to be directed into the teeth 9 from their ends.

While a particular construction of the cutting bits and the downwardly extending legs has been

shown, it will be apparent that the invention is independent of these features and may be used in any construction of drill bit in which washing of the cutting edges is desired.

What I claim is:

1. A roller cone rock bit comprising: a shank, downwardly depending legs on said shank, an extended flange portion on said shank between said legs, a downwardly facing concave rounded central section on said shank between said legs, conically shaped cutter cones rotatably supported from said legs, a circumferential row of teeth at the base of each cone, a circular central fluid channel extending axially downward through said shank, means across the lower end of said channel substantially reducing the diameter thereof; said concave section forming a close fit with the adjacent base end of said teeth, discharge conduits extending radially outward from said channel and opening at said concave section at a position of vertical alignment with and above the center line of said cone and adjacent said base end of said teeth, said conduit including an abrupt bend intermediate its length whereby fluid passing through said conduit is adapted to discharge out of said conduit over the base end of said teeth and pass along the sides of consecutive teeth and parallel to the bottom of said teeth for cooling and flushing purposes.

2. A roller cone rock bit comprising: a shank, an upper threaded portion on said shank, downwardly depending legs on said shank, an extended flange portion on said shank between said legs, a downwardly facing concave rounded central section on said shank between said legs, conically shaped cutter cones rotatably supported from said legs, a circumferential row of teeth at the base of each cone, a circular central fluid channel extending axially downward through said shank, a baffle plate across the lower end of said channel substantially reducing the diameter thereof; said concave section forming a close fit with the adjacent base end of said teeth, discharge conduits extending radially outward from said channel near said baffle plate and opening at said concave section at a position of vertical alignment with and above the center line of said cone and adjacent said base end of said teeth, said conduit including an abrupt bend intermediate its length whereby fluid passing through said conduit is adapted to discharge out of said conduit over the base end of said teeth and pass along the sides of consecutive teeth simultaneously and parallel to the bottom of said teeth for cooling and flushing purposes, a portion of said fluid passing through said reduced diameter and combining with said first mentioned fluid below said discharge opening.
